UNITED STATES PATENT OFFICE.

LEONIDAS NICHOLAS LYON, OF HOUSTON, TEXAS.

DOOR FASTENER.

Application filed July 24, 1922. Serial No. 577,146.

To all whom it may concern:

Be it known that I, LEONIDAS N. LYON, a citizen of the United States, residing at Houston, in the county of Harris and State 5 of Texas, have invented a new and useful Door Fastener, of which the following is a specification.

This invention aims to provide a simple means for locking the doors of freight cars 10 and the like, so that the doors cannot be opened readily, should the seal thereon be broken.

It is within the province of the disclosure to improve generally and to enhance the 15 utility of devices of that type to which the invention appertains.

With the above and other objects in view, which will appear as the description proceeds, the invention resides in the combination 20 and arrangement of parts and in the details of construction hereinafter described and claimed, it being understood that, within in the scope of what is claimed, changes in the precise embodiment of the invention 25 shown can be made without departing from the scope of the invention.

In the accompanying drawings:—

Figure 1 shows in top plan, a device constructed in accordance with the invention, 30 parts appearing in section; Figure 2 is a cross section on the line 2—2 of Figure 1; Figure 3 is a cross section on the line 3—3 of Figure 1; Figure 4 is a cross section on the line 4—4 of Figure 1; and Figure 5 is 35 an end elevation.

In the drawings the numeral 1 denotes the closure door of a freight car, or the like. On the outer surface of the door 1, a support 2, in the form of a plate, is secured as indicated at 3, the support being provided with approximately parallel flanges 4 having outstanding lips 5 adapted as indicated at 6 to be secured to the rear edge of the door 1. A vertical pivot element 7 is carried by the 45 flanges 4.

The device includes a box-like latch member 8 comprising a front 9, a top 10 a bottom 11, and ends 12 and 14, the end 12 being provided with an opening 15. The front 9 50 of the latch member 8 carries outwardly prolonged extensions 16 supplied with elongated slots 17. The extensions 16 are received between the flanges 4 of the support 2 and are spaced apart less widely than are the 55 flanges 4, the pivot element 7 being received in the elongated slots 17. The construction

is such that the latch member 8 may swing inwardly and outwardly on the pivot element 7, and may have, also, a vertical movement on the pivot member. 60

Keepers 18 and 20 project inwardly from the front 9 of the latch member 8, the keeper 18 being provided with a downwardly extended seat 19, and the keeper 20 being provided with a downwardly extended seat 21. 65

An anchor plate 22 is secured at 23 to the body 24 of the car and has an outstanding guard 25, within which the latch member 8 is received, when the latch member is in a closed position. The anchor plate 22 carries 70 an outstanding keeper 26, located between the keepers 18 and 20 of the latch member 8 when the latch member is in a closed position, the keeper 26 on the anchor plate having a downwardly extended seat 27 defining 75 an upstanding lug 28.

A bolt 29, which may be in the form of a nail having a head 30, is supported on the lug 28 of the keeper 26 on the anchor plate 22, and, when the latch member 8 is swung 80 to the closed position shown in Figure 1, on the pivot element 7, the keeper 18 and 20 on the latch member engage the bolt 29 and carry the bolt inwardly, transversely of its length, the bolt dropping downwardly into 85 the seat 19 of the keeper 18 on the latch member 8, into the seat 27 of the keeper 26 on the anchor plate 22 and into the seat 21 on the keeper 20 of the latch member 8, as shown in Figures 2, 3 and 4, the latch 8 being held on the keeper plate 22, so that the latch member cannot be swung to an open position. 90

It is impossible to withdraw the bolt 29, without bending the bolt, when the bolt is disposed as shown in Figure 1, because the end 12 of the latch 8 lies in the path of the bolt 29 when the bolt is moved longitudinally. It is possible, however, to insert a prize tool through the opening 15 in the end 12 and bend the bolt 29, whereupon the bolt may be withdrawn. The withdrawal of the bolt 29, therefore, will be attended with considerable difficulty and will necessitate the use of tools. The structure forming the subject matter of this application 95 preferably is located far enough down from the top of the car, so that a person lying on the top of the car cannot reach the device, and, likewise, the structure is located far enough from the surface of the ground 100 so that a person standing upon the ground 110 cannot gain access to the locking bolt 29.

These circumstances, coupled with the further fact that the locking bolt 29 must be bent and withdrawn forcibly, make it exceedingly difficult for a person to gain unauthorized access to the car. Since the latch member 8 has a vertical movement on the pivot element 7, a vertical adjustment of the latch member with respect to the support 2 and the anchor plate 22 will be possible, and 10 the latch member may be always swung into the closed position depicted in Figure 1.

What is claimed is:—

1. In a device of the class described a support, a latch member pivoted to the support, 15 and an anchor wherewith the latch member coacts, the latch member and the anchor having keepers provided with seats; and a bolt adapted to be mounted on the keeper of the anchor, the keeper of the latch member 20 engaging the bolt upon closing movement to move the bolt transversely and to cause the bolt to drop into the seats of the keepers.

2. A device of the class described, constructed as set forth in claim 1, and further 25 characterized by the fact that the latch member is provided with a wall, located in the path of the bolt and preventing the bolt from being withdrawn from the seats of the keepers by a right line movement, said wall 30 having an opening, giving access to the bolt and permitting a bending of the bolt and a withdrawal thereof.

3. In a device of the class described, a support; a latch member; means for 35 mounting the latch member on the support for pivotal movement and for sliding movement into two rectangularly disposed directions; an anchor wherewith the latch member coacts, the latch member and the anchor 40 having keepers provided with seats; and a bolt adapted to be supported on the keeper of the anchor, the keeper of the latch member engaging the bolt upon closing movement to move the bolt transversely and to

cause the bolt to drop into the seats of the 45 keepers.

4. In a device of the class described, an anchor; a pivotally mounted latch member cooperating with the anchor; a bolt supported on the anchor for dropping movement when the bolt is moved transversely; and cooperating elements on the anchor and the latch member wherewith the bolt coacts, 50 when the bolt drops, the latch member engaging the bolt to move the bolt transversely 55 into such a position that it may drop and engage with said elements.

5. A device of the class described, comprising members which are relatively movable, and a locking element movably supported on one of said members, said members comprising parts which coact with the locking element to hold said members against separation, after said members have been brought together and after the locking element has been moved and permitted to drop, 60 the other of said members having means for moving the locking element to dropping position when said members are brought together. 65

6. A device of the class described, constructed as set forth in claim 5, and further characterized by the fact that one of said members is provided with means for preventing the locking element from being disengaged from said parts when the locking element is in a normal position, the locking element being capable of distortion, to permit it to pass said means and to be disengaged from said parts. 70

In testimony that I claim the foregoing as my own, I have hereto affixed my signature in the presence of two witnesses:

LEONIDAS NICHOLAS LYON.

Witnesses:

H. M. W. EREHEIMER,
E. DREYLING.
